CLAIM

The ornamental design for a medical splint, as shown.

DESCRIPTION

FIG. 1 is a perspective view of a medical splint, showing our new design; the broken line showing is for illustrative purposes only and forms no part of the claimed design; FIG. 2 is an inside perspective view of the medical splint laid flat;

FIG. 3 is an outside perspective view thereof;

FIG. 4 is a longitudinal side edge view of the medical splint, the opposite side edge being a mirror image thereof; and, FIG. 5 is an end view of the medical splint, the opposite end being a mirror image thereof.
